(57) **CLAIM**

The ornamental design for a pipe fitting, as shown and described.

DESCRIPTION

FIG. 1 is a perspective view of the pipe fitting according to the present disclosure.

FIG. 2 is a front view of the pipe fitting according to the present disclosure.

FIG. 3 is a back view of the pipe fitting according to the present disclosure.

FIG. 4 is a left side view of the pipe fitting according to the present disclosure.

FIG. 5 is a right side view of the pipe fitting according to the present disclosure.

FIG. 6 is a top plan view of the pipe fitting according to the present disclosure; and,

FIG. 7 is a bottom plan view of the pipe fitting according to the present disclosure.

The broken lines showing interior details in FIG. 7 are included for the purpose of illustrating portions of the pipe fitting and form no part of the claimed design.
